STOOL OR SIMILAR ARTICLE

Merle C. Melchior, Los Angeles, Calif., assignor of one-half to Sidney Galper, Los Angeles, Calif.

Filed Sept. 29, 1964, Ser. No. 81,924

Term of patent 14 years

(Cl. D15—8)

FIGURE 1 is a perspective view of a small stool wherein the seat is formed of a web and cushion arrangement and a pair of matching tubular bars extend along the base and top thereof;

FIGURE 5 is a perspective view of the stool of FIGURE 1 wherein the seat is formed of a one-piece rigidified member and wherein the upper pair of matching tubular bars have been omitted;

I claim:

The ornamental design for a stool or similar article, substantially as shown.
